UNITED STATES PATENT OFFICE.

RANDOLPH CROMPTON, OF MARLBORO, NEW HAMPSHIRE.

METHOD OF SPINNING YARN.

1,060,233.

Specification of Letters Patent. Patented Apr. 29, 1913.

Application filed July 25, 1912. Serial No. 711,414.

To all whom it may concern:

Be it known that I, RANDOLPH CROMPTON, a citizen of the United States, and resident of Marlboro, county of Cheshire, State of New Hampshire, have invented an Improvement in Methods of Spinning Yarn, of which the following description, in connection with the accompanying drawing, is a specification, like characters on the drawing representing like parts.

This invention has for its object the production of a novel method of spinning yarn whereby the yarn may be laid upon the yarn receiver or bobbin with two successive windings in reverse directions but with the twist of the yarn the same throughout both windings.

In United States Patent No. 914,703 granted to me March 9, 1909 I show a shuttle equipped with means to sever the yarn drawn off from the filling carrier when a reversal in the direction of winding of the yarn is reached. The filling carrier wound for use in connection with such a shuttle has a few winds laid thereon in one direction, sufficient for one or more picks of the shuttle, across the lay, and the remaining winds of filling on the filling carrier were wound in a reverse direction. The mechanism shown and described in my patent operates in the loom with great accuracy and with entire satisfaction, but the practical objection to its extended use has been due to the fact that after the yarn has been spun upon a set of filling carriers in usual manner it must be re-wound upon a second set of filling carriers by means of a winding machine, in which the filling carriers are rotated first in one direction and then in the reverse direction. Heretofore it has not been possible to spin the yarn directly upon the yarn carrier with two windings in reverse directions, because the reversal of the winding reversed the twist in the yarn and thereby weakened and caused breakage of the yarn.

In my efforts to overcome the objections hereinbefore noted I have discovered that by a simple manipulation of the filling carriers or bobbins in the spinning frame after the initial or primary winding of yarn is spun I can proceed with the spinning of the secondary or final winding, in a reverse direction, and without any alteration or variation in the twist of the yarn. By my present invention I am thus able to spin the yarn directly upon the filling carriers with

two windings in reverse directions but with the same twist, so that the yarn is of uniform strength throughout. I am also able, by my present invention, to spin the yarn on any usual or well known form of ring spinning frame.

The novel features of my invention will be described in the subjoined specification and particularly pointed out in the following claims.

Figure 1 is a view of a sufficient portion of a usual ring spinning frame showing the filling carriers positioned for the winding thereupon of the initial winding of the yarn; Fig. 2 is a similar view, but showing the filling carriers inverted and in readiness for the secondary or final winding of the yarn thereupon, but before the rail is depressed. Fig. 3 is an enlarged view in elevation of a filling carrier with the two windings of yarn thereupon.

Referring to Figs. 1 and 2, 1 indicates a spindle rail, 2 the vertically reciprocating ring-rail, 3 rings mounted on the ring-rail and having travelers 4, through which the yarn 5 is led from the usual drawing rolls (not shown) to the filling carrier or bobbin, and at 6 I have shown rotating spindles mounted on the rail 1 and provided with suitable whirls 7, all of well known or usual construction in ring spinning frames.

In accordance with my present invention I place the filling carriers or bobbins 8 on the spindles with their butt ends uppermost, and the frame is started, with the ring-rail in proper position to lay a primary or initial winding 9, Fig. 1, of yarn upon the filling carrier at the desired distance from the butt end thereof. A suitable amount of yarn is so wound, sufficient for one or more picks of the shuttle across the lay, and then the frame is stopped. I now doff the frame, removing the partly wound filling carriers from the spindles, and I invert or turn the filling carriers end for end, and replace them upon the spindles with their tips uppermost, as is usual, see Fig. 2. The frame is now started up and the spinning operation is resumed, and a secondary or final winding 10 of yarn is laid upon the filling carriers until they are properly filled, as shown in Fig. 3, whereupon the operation is completed and the frame is doffed, the filling carriers then being ready to be used in the loom. It will be observed that no change is made in the direction of rotation

of the filling carriers by my method, nor is there any alteration in the relationship between the various parts of the spinning frame as the yarn is delivered. It is customary to wind yarn with the right hand wind, and it is so laid upon the filling carrier 8 when the primary winding 9 is spun thereupon, but when said filling carrier is removed from the spindle and inverted it will be obvious that the yarn will have the left hand wind when drawn off in the loom shuttle. The secondary winding 10 is laid with the right hand wind and it so remains, but the inversion of the filling carrier between the initial and final windings causes said windings to be laid with the wind in reverse directions, as will be apparent. Inasmuch, however, as there is no change in the direction of rotation of the spindle or in the lead of the yarn from the ring to the filling carrier there is no change or variation in the twist, either as to its direction or amount, and in consequence the twist of the yarn is the same, and uniform, from the beginning to the end of the operation of spinning.

The time requisite to doff and invert the filling carriers after the primary winding has been laid is short, the doffing is easily accomplished, and if performed with reasonable care no ends will be broken, as all that is necessary is to provide enough slack yarn for the proper inversion of the filling carrier.

By the process hereinbefore set forth I get a filling carrier having two windings of yarn thereupon with the winds in reverse directions and with the same twist throughout the winding, and without requiring any change in the structure of the usual ring spinning frame, the filling carrier spun in accordance with my invention being at once ready for use in the loom shuttle in accordance with the disclosures in my patent hereinbefore referred to.

Having fully described my invention, what I claim as new and desire to secure by Letters Patent is:

1. The herein described method of laying yarn upon a filling carrier, which consists in spinning a desired quantity of yarn upon the filling carrier, arresting the spinning and turning the filling carrier end for end, and resuming the spinning to complete the laying of yarn upon the inverted filling carrier, whereby the two windings are spun with the same twist but with the winds in opposite directions.

2. The herein described method of spinning yarn upon a filling carrier, which consists in rotating the filling carrier and spinning a desired quantity of yarn thereupon, stopping the rotation of the filling carrier and turning it end for end, resuming the rotation of the filling carrier in the original direction, and completing the spinning of the yarn thereupon, whereby the primary and secondary windings will be laid in opposite directions but with the same twist throughout.

3. The herein described method of spinning yarn upon a filling carrier, which consists in placing the filling carrier on a spindle, rotating the latter, and laying a desired volume of yarn, with a predetermined twist, upon the filling carrier, stopping the spindle and inverting the filling carrier thereon, resuming the rotation of the spindle and the inverted filling carrier, and laying a second volume of yarn upon the filling carrier with the original twist, the inversion of the filling carrier causing the two volumes of yarn to be wound thereupon in opposite directions.

In testimony whereof, I have signed my name to this specification, in the presence of two subscribing witnesses.

RANDOLPH CROMPTON.
